J. H. POPE

ATTACHING MACHINE

Filed July 23, 1921

Fig. 1.

Patented Nov. 20, 1923.

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

ATTACHING MACHINE.

Application filed July 23, 1921. Serial No. 487,044.

To all whom it may concern:

Be it known that I, JOSEPH H. POPE, a citizen of the United States, residing at Hamilton, in the county of Essex and State of Massachusetts, have invented certain Improvements in Attaching Machines, of which the following description, in connection with the accompanying drawings, is a specification, like reference characters 10 on the drawings indicating like parts in the several figures.

This invention relates to attaching machines, as those in which nails, tacks or other fasteners are driven to secure various elements. It is especially applicable to shoe machines, being here illustrated in connection with apparatus for attaching counters. Such apparatus furnishes an instance of the need for driving fasteners in 20 varying positions, determined by conditions surrounding the parts associated, but not necessarily directly connected, with the part to be attached. In applying molded counters to turn shoes in accordance with 25 the method of Patent No. 1,368,373, Toothaker, Feb. 15, 1912, a counter with a tuck or shank-piece stapled thereto is secured to the sole by nails, customarily four in number, driven in the area between the 30 center of the heel-seat and the breast-line. To permit proper attachment when a wood heel is to be applied to the shoe and nailed from the inside, as is usual, the heel-attaching nails must, of course, clear the previously driven counter-attaching nails, and 35 these heel-attaching nails vary in position for different sizes and types of heels. Moreover, as the form of heel changes, the position of the heel-breast longitudinally 40 of the shoe also changes, so that a nailing design for the counter which fell within the heel-seat area for one form might be outside for another, causing the counter-attaching nails to pass through the shank- 45 portion of the sole. It is consequently important that such machines as those for attaching counters should include means for altering the nailing design to correspond to the conditions existing in the particular shoe operated upon. In accordance 50 with a practice which has heretofore obtained, the die-block and counter-holding block of the counter-attaching machine, and also the loader-block which is to deliver to the die-block, has been provided

with a plurality of sets of nail-receiving openings, so situated that some one of them will furnish a nailing design which will co-operate correctly with any form of heel which is to be applied to the shoe upon 60 which the machine has acted. The nail-distributor of the machine has been furnished with a corresponding number of removable foot-plates for the tube-holder, each plate provided with delivery-openings, 65 in which the tubes may be inserted, equal in number and corresponding in arrangement to one of the sets of receiving-openings of the loader-block. Such an organization, involving the interchange of plates 70 and the complete transfer of the tubes from the openings of one plate to those of another for each nailing design employed, proves so burdensome to the operators that they neglect it, and upon a change in the 75 style of the shoe will continue the use of the design for attaching the counter of the previously operated-upon shoe, which may cause the difficulties indicated above. It is an object of my invention to provide 80 an attaching machine having means for changing the nailing design, which means is simple in construction, and is so readily operated that its use will seldom be neglected. 85

A particular embodiment of my invention is illustrated in the accompanying drawing,

Figure 1 being a broken perspective view of portions of a counter-attaching machine including said invention;

Fig. 2, a vertical, sectional detail through the foot-plate of the distributing apparatus and the associated loader-block;

Fig. 3, a perspective view of a shoe with the counter attached, as by the machine 95 of the present invention; and

Fig. 4, a broken side elevation of the heel-portion of a shoe, illustrating the relation between the counter-attaching and heel-attaching nails for heels of different forms.

Generally, the machine shown resembles, in its work-supporting, pressure-applying and nail-driving mechanisms, the well-known Lightning heel-attaching machine, which need not here be described. The die-block 10 and one of the side-rods 12 of this apparatus appear in Fig. 1. Upon the under side of the die-block is mounted the most essential distinguishing element of the counter-attaching machine, which con-

sists of a counter-holding block 14, having nail-receiving openings 16 alined with the corresponding openings of the die-block. This block 14 is so formed and arranged as to receive and hold the counter to be attached for co-operation with the jacked shoe. It has been found that the counter may be satisfactorily fastened to the sole of a turn shoe by use of four nails *n*, related as in Fig. 3 of the drawing. Here is shown the upper of a shoe *S* in place upon a last *L*, and applied to it a counter *C*, to which is secured, by staples *s*, a shank piece *P*. The counter-attaching nails *n* pass through the shank-piece at opposite sides of the longitudinal axis of the shoe and at points somewhat to the rear of the breast-line of the heel, they being preferably arranged at the corners of a rectangle. To bring these nails within the heel-seat area and clear of the path of the attaching nails *N* for a wood heel *H*, such as is illustrated in Fig. 4, the position of the counter-nails may be varied longitudinally of the shoe, three locations of the same design having been found generally sufficient to establish the proper relations between the elements. The corresponding three sets of nail-receiving openings are indicated in Fig. 1 at *a*, *b* and *c*, respectively.

Carried upon the frame of the machine is a nail-distributing apparatus, including flexible nail-tubes or conduits 18 mounted in a suitable holder 20, which has a foot-plate 22 in which the tubes terminate. In this foot-plate is shown an opening 24, rectangular in form, to receive a plate-section 26, the length of which is such that a movement of the section is permitted at least as great as the distance between the most widely separated sets of die-openings *a* and *c*. The plate-section may be guided in the opening by a rod 28 passing through a horizontal bore in the section and entering openings 30, 30 in the foot-plate, this rod being held in place by a set-screw 32 threaded through the top of the section. In the portion 26 is an opening 34 for each of the tubes 18, these corresponding in arrangement to each of the sets of die-openings *a*, *b* and *c*. Fulcrumed upon the foot-plate is a lever 36, connected to the section 26, conveniently by a slot through which the set-screw 32 passes. At the free end of the lever is an upturned end 38, serving as a finger-piece, and adjacent to this is an opening, which may receive any one of three pins 40 arranged upon the arc of a circle about the fulcrum of the lever, the adjacent pins being spaced from each other to give settings of the plate-section, under the influence of the lever, to correspond to the three sets of die-openings.

To transfer the nails from the distributing mechanism to the receiving-openings of

the die and counter-holding blocks, loading mechanism is provided, including an arm 42 arranged to turn about the side-rod 12 and carrying the customary loader-block 44 with its movable nail-supporting shutter 45. In this loader-block are sets of nail-receiving openings 46, corresponding to those of the die-block and movable into alinement therewith. In the opposite extreme of movement of the loader-arm, when it is caught by a latch 48, the openings 46 lie beneath some one of the positions of the openings 34 of the foot-plate-section, as determined by the engagement of the adjusting lever with the pins 40.

Assume now that such a heel *H* is to be attached as is shown in full lines in Fig. 4 of the drawing, with its attaching nails being located as appears at *N*. For this heel the nailing design for the counter-attaching machine, furnished by the set *a* of die-block-openings may be correct. If the style of heel to be attached changes, as to that appearing in dotted lines at *h* in Fig. 4, the inner pair of nails *n* of the previous nailing will be outside the breast-line of the heel, so that their points will appear through the sole, in which case the lever 36 may be shifted to the next pin 40, bringing the nail-delivering tubes into position to supply the set *b* of receiving openings, which will locate the nails *n* safely within the heel-seat area. Or such an arrangement of heel-attaching nails may be desirable that the location of the set *c* of die-block-openings may be the preferable one, in which case the adjustment of the foot-plate-section 26 to bring about this delivery may be effected by the movement of its controlling lever to the third pin. While three sets of openings have been described, it is obvious that, within limits, any other number might be employed, and that more or less than four openings in each set is possible.

Having described my invention, what I claim as new and desire to secure by Letters Patent of the United States is:

1. In an attaching machine, a receiving member having a plurality of sets of fastener-receiving openings, a plurality of fastener conduits, a movable member common to plural conduits and having delivery-openings in which said conduits terminate, and means arranged to bring the delivery-openings into co-operation with one or another of the sets of receiving openings.

2. In an attaching machine, a receiving member having a plurality of sets of fastener-receiving openings, the openings of the different sets being similarly related, a plurality of fastener-conduits, a movable member having delivery-openings in which the conduits terminate, said delivery-openings corresponding in number and relation to a set of receiving openings, means ar-

- ranged to bring the delivery-openings into co-operation with one or another of the sets of receiving openings, and means arranged to move the delivery member to register its openings with any set of receiving openings.
3. In an attaching machine, a receiving member having a plurality of sets of fastener-receiving openings, a plurality of fastener-conduits fixed against movement at their receiving ends, and a reciprocatory plate provided with openings to receive the delivery end of the conduits and co-operating with the fastener-receiving openings.
4. In an attaching machine, a tube-holder, flexible fastener-tubes mounted therein, and a foot-plate having a unitary movable section provided with openings in which the tubes terminate.
5. In an attaching machine, a transferring device having a plurality of sets of fastener-receiving openings, a tube-holder with which the transferring device co-operates, flexible fastener-tubes mounted in the holder, a foot-plate having a unitary movable section provided with openings in which the tubes terminate, and means for fixing the section in different positions corresponding to the different sets of receiving openings of the transferring device.
6. In an attaching machine, a tube-holder, flexible fastener-tubes mounted therein, a foot-plate having an opening, a plate arranged to slide in the opening and provided with tube-receiving openings, and means for fixing the plate in different positions.
7. In an attaching machine, a tube-holder, flexible fastener-tubes mounted therein, a foot-plate having an opening, a perforated plate arranged to slide in the opening and to the perforations of which the tubes are connected, a lever fulcrumed upon the foot-plate and connected to the sliding plate, and means for fixing the lever in different positions.
8. In an attaching machine, a tube-holder, flexible fastener-tubes mounted therein, a foot-plate having a movable section provided with openings in which the tubes terminate, a lever fulcrumed upon the plate and pivoted to the section, and a plurality of positioning projections for engagement with the lever.
9. In an attaching machine, a tube-holder, flexible fastener-tubes mounted therein, a foot-plate having an opening, a plate arranged to slide in the opening and provided with tube-receiving openings, said sliding plate having guide-projections entering openings in the foot-plate, and means for fixing the sliding plate in different positions.
10. In an attaching machine, a tube-holder, flexible fastener-tubes mounted therein, a foot-plate having an opening, a perforated plate arranged to slide in the opening and provided with tube-receiving openings, a rod passing through an opening in the sliding plate and entering openings in the foot-plate, a screw threaded through the sliding plate and contacting with the rod to retain it in place, and a lever fulcrumed upon the foot-plate and engaging the screw.
11. In a counter-attaching machine, a counter-holding member having a plurality of sets of receiving openings, loading mechanism provided with sets of fastener-openings movable into alignment with those of the counter-holding member, and fastener-distributing mechanism with which the loading mechanism co-operates, said distributing mechanism including delivering means movable into alignment with any one of the sets of fastener-openings.
12. In a counter-attaching machine, a counter-holding member having a plurality of sets of receiving openings, loading mechanism provided with sets of fastener-openings movable into alignment with those of the counter-holding member, and distributing mechanism with which the loading mechanism co-operates, said distributing mechanism including fastener-delivering tubes corresponding in number to one of the sets of fastener-openings and movable into alignment with any of said sets.
13. In a counter-attaching machine, a counter-holding member having a plurality of sets of receiving openings, loading mechanism provided with sets of fastener-openings movable into alignment with those of the counter-holding member, and fastener-distributing mechanism with which the loading mechanism co-operates, said distributing mechanism including a foot-plate having a section containing openings corresponding to a single set of the fastener-openings and being movable to bring said openings into alignment with any one of the sets.

In testimony whereof I have signed my name to this specification.

JOSEPH H. POPE.
